(57) **CLAIM**

The ornamental design for a vessel lid, as shown and described.

DESCRIPTION

The patent or application file contains at least one drawing executed in color. Copies of this patent or patent application publication with color drawing(s) will be provided by the Office upon request and payment of the necessary fee. FIG. 1 is a perspective view of a vessel lid showing my new design;

FIG. 2 is a front view thereof;

FIG. 3 is a back view thereof;

FIG. 4 is a left side view thereof;

FIG. 5 is a left side view thereof;

FIG. 6 is a top view thereof; and,

FIG. 7 is a bottom view thereof.

The de-emphasized and half-tone portions shown within the broken lines in the drawing views depict portions of the vessel lid that form no part of the claimed design.

1 Claim, 7 Drawing Sheets
